VEGETABLE AND FRUIT WASHER

Arthur B. McLauchlan, Salem, Oreg.

Application February 28, 1948, Serial No. 11,911

3 Claims. (Cl. 134—120)

1

This invention relates in general to washers, such, for example, as washers for vegetables and fruits and the like, in which the articles to be washed are required to be moved along the washer while being subjected to a washing action by water or other washing liquid.

This invention relates particularly to washers in which the articles to be washed are totally or partially submerged in the washing water during part of the time required for their passage through the washer.

This invention is also especially concerned with the washing of string beans or other articles in which, in addition to the actual washing, it is desirable to have the washed beans delivered from the washer in parallel alignment as an aid to the placing of the same in cans or jars, as hereinafter explained.

One of the objects of this invention is to provide an improved washer in which the articles to be washed will be moved in predetermined direction through an agitated tank of water without necessitating any large or constant flow of water for the purpose of moving the articles. A related object is to provide an improved washer in which the movement of the articles will continue beyond the washing water and over a screen or grating so as to permit draining or rinsing or partial drying of the washed surfaces of the articles as a continuation of the washing process.

A further special object of this invention is to provide an improved washer for elongated articles, particularly string beans, in which they will automatically be delivered in parallel alignment to facilitate the placing of the same in containers, as is required in the ordinary canning of string beans.

An additional object of the present invention is to provide a washer which will be relatively simple in construction and operation and in which a large quantity of string beans, for example, can be handled with a minimum amount of manual labor.

The manner in which these objects and other advantages are attained by means of my device will be explained in the course of the following description of the construction and operation of the same, in which description reference is made to the accompanying drawings.

In the drawings:

Fig. 1 is a sectional elevation of the washing pan with the associated supporting and actuating members, taken on line 1—1 of Fig. 2, a portion of the side wall of the washing pan being

broken away to show the structure of the washing pan more clearly;

Fig. 2 is a plan view of the washing pan and associated members, a portion of the top cover being shown broken away for the sake of clarity;

Fig. 3 is a fragmentary, vertical section corresponding to lines 3—3 of Figs. 1 and 2;

Figs. 4 and 5 are fragmentary side elevations of the washing pan, partly in section, illustrating the position of the same at the beginning of each forward and rearward vibratory movement or stroke, respectively;

Fig. 6 is a more or less diagrammatic plan view of the washing pan, with the cover removed, illustrating the effect of the composite vibratory movement on string beans deposited in the washing pan;

Fig. 7 is a fragmentary, vertical, longitudinal section of the rear end of the washing pan, corresponding approximately to the line 7—7 of Fig. 6, but drawn to a larger scale;

Fig. 8 is a fore-shortened fragmentary, transverse section on line 8—8 of Fig. 1, being drawn to a larger scale, showing the operating mechanism for the washing pan and the supporting mounting for one end of the pan; and

Fig. 9 is a side elevation of a complete washer and drier embodying my invention, this elevation being taken on the opposite side from which Figs. 1, 4 and 5 were taken.

Since my washer may or may not be used in combination with the companion drier shown in Fig. 9, I shall first describe the washer itself.

The washer includes a washing pan indicated in general by the reference character 10, which is mounted for special vibratory motion in a rigid frame structure indicated in general by the reference character 11. The frame structure comprises vertical supports with longitudinal and lateral members joined in such a manner as to form a suitably strong and rigid skeleton frame structure.

A pair of vertical members or tubular posts 12 and 13 (Fig. 1) are secured to each side of the frame structure and a bracket 14 is adjustably mounted on each of these four posts and is retained at the desired height thereon by set screws. The brackets 14 support transverse shafts 15 and 16. A pair of arms 17 are rockably mounted on the forward shaft 15, the arms being located at opposite sides of the frame 11, and a similar pair of arms 18 are mounted on the rear shaft 16. The mounting for these arms will be described in more detail later.

The washing pan 10 has a flat bottom 19,

which slopes upwardly from the rear to the front end of the pan, a pair of vertical side walls 20, and a rear wall 21. Near the forward end of the washing pan the upwardly sloping bottom 19 joins a transversely extending trough portion 22, and the side walls 20 are extended downwardly so as to provide end walls for this trough portion. Beyond the trough portion 22 a final bottom section 23 continues for a short distance in the same upwardly sloping plane as the main bottom 19. The side walls 20 preferably converge slightly towards each other at this final section of the washing pan (as shown at 20' in Fig. 2) in order to make the discharging end of the washing pan narrower as a convenience in enabling an operator to reach from one side of the discharging end to the other.

A removable screen or grating 24 is set over the trough portion 22, and the top of the trough is recessed sufficiently so that the top surface of this grating 24 will be flush with the top faces of the main bottom 19 and the final bottom section 23. Thus the main bottom wall 19, the grating 24 and the final bottom section 23 constitute together a continuous upwardly sloping surface from the rear end of the washing pan to the forward or discharging end. This upwardly sloping bottom surface in the washing pan is an important element in my device. A discharging drain pipe 25 leads from the bottom of the trough portion 22.

A stationary tubular section 26 of a telescoping fixture is rigidly secured to the outside of each of the side walls 20 of the washing pan (see Fig. 1). The rockable arms 17 have their upper ends pivotally connected to these tubular sections 26 respectively. A telescoping member 27 is mounted in each tubular section 26 and the rockable arms 18 are pivotally connected to these telescoping members 27 respectively. The telescoping members 27 are held in fixed position in the tubular sections 26 by suitable set screws. Thus the entire washing pan, including the trough portion 22 and the final bottom section 23, is supported on the two pairs of rockable arms 17 and 18. The arms of each pair are parallel but, as will be observed from Fig. 1, the two pairs of arms 17 and 18 are not parallel to each other, and the rear pair of arms 18 are inclined rearwardly at a greater angle from the vertical than the forward pair of arms 17. This particular and nonparallel positioning of the two pairs of rockable supporting arms performs a most important function to be hereinafter explained.

The manner in which the pair of rockable arms 17 are mounted on the forward shaft 15 will now be described with reference to Fig. 8:

The shaft 15 is formed with an integral annular shoulder 28 spaced from each end, one such shoulder being shown in Fig. 8. A hollow shaft or sleeve 29 is carried by the shaft 15 and is supported at each end by a cylindrical bearing 30 of resilient material such as rubber. The arms 17 are rigidly secured to the ends of the hollow shaft or sleeve 29. A metal washer 31, freely mounted on the shaft 15, bears against the outer end of the resilient bearing 30. A metal sleeve 32, which is split longitudinally, is placed on the end of the shaft 15 and extends slightly beyond the end of the shaft. A screw 33, threaded in the end of the shaft 15, has a head which bears against the outer end of the split sleeve 32. Thus tightening of the screw 33 results in axial compression and radial expansion of the

resilient bearing 30. The resilient bearing 30 is prevented, under such axial compression, from rotating on the shaft 15 and the hollow shaft or sleeve 29 is similarly prevented from rotating on the resilient bearing 30, but, due to the resiliency of the bearing 30, the hollow shaft or sleeve 29, and with it the arms 17, can be given a limited oscillating motion while the supporting shaft 15 remains stationary. The split sleeve 32 is clamped in the bracket 14 by a pair of clamping bolts, thus holding the shaft 15 against rotation. When it is desired to adjust the screw 33, the clamping bolts are first loosened to permit the split sleeve 32 to slide on the shaft 15. Similar mounting elements are provided at both ends of the shaft 15, as apparent from Fig. 8.

A pair of arms 34 and 35 (Fig. 8) are firmly clamped on the hollow shaft or sleeve 29 and these arms in turn carry a knuckle joint composed of a pair of T-shaped sleeve members 36 and 37. The T-shaped sleeve member 36 and 37 are secured on the arms 34 and 35 respectively by set screws. The T-shaped sleeve member 36 has a stem 36' which is threaded on its outer cylindrical surface and which engages the threads in a corresponding recess formed in the stem 37' of the other T-shaped sleeve member 37. A tubular bearing 38 of resilient material is carried on the stem 37' and is encompassed by a clamping member 39. The clamping member 39 has an integral lower portion in the form of a sleeve 39' which is adapted to be secured by means of a set screw to a pitman rod 40 (Fig. 1). The pitman rod 40 is attached to an annular bearing ring 41 which is mounted on an eccentric disc 42 and the eccentric disc 42 is rotated by means of a motor 43. The rear pair of arms 18 of the washing pan are mounted on the shaft 16 in the same manner in which the forward arms 17 are mounted on the shaft 15.

A pair of overlapping spaced baffle plates 44 and 45 (Fig. 7) extend across the washing pan at the rear or intake end, one plate being secured to the rear wall 21 and the other plate being secured to the bottom wall, and both plates secured at their ends to the side walls 20 of the washing pan. These two baffle plates form a transversely extending louvre opening through which the water, delivered into the washing pan through the inlet 46, passes. A hose 48 is detachably connected to the bottom end of the inlet pipe 46. The rear wall 21 of the washing pan terminates at the top in a flange 49 extending a slight distance inwardly.

A conveyor, indicated in general by the reference character 50 (Figs. 1 and 9) has its discharging end supported at the top of the rear end of the frame 11. The conveyor includes a motor-driven endless belt 50, provided with suitable cleats which operate to convey the beans, or other articles to be passed through the washer, from the bottom of a hopper 51 to the discharging end of the conveyor above the rear end of the washing pan 10 so that the beans are delivered into the washing pan as they drop from the top of the conveyor belt. The hopper 51 is preferably formed with a screen bottom wall 52 through which bits of trash, gravel, etc., can pass and thus be eliminated before the washing process. The conveyor has a removable cover 53 which, at the upper discharging end of the conveyor, fits against a hood 54 extending over the major portion of the washing pan 10. The hood 54 (Fig. 3) is suspended from U-shaped supporting members 55 which in turn have their ends removably secured along the top of the

5

frame 11 at the sides. The hood 54 has no direct contact with the washing pan 10 itself, and thus the vibratory movement of the washing pan is not transmitted to the hood 54 or to any portion of the conveyor 50.

A plurality of shower pipes 56 (Fig. 2) are arranged transversely across the frame 11 above the grating 24. These pipes are provided on their under side with perforations or small nozzles by means of which water delivered into the pipes can be sprayed onto the beans or other objects passing over the grating 24. Preferably the shower pipes 56 are connected at their ends through rotatable bearings with the supporting connecting pipes 57, and handles are provided so that each shower pipe can be turned to cause the sprays or showers to be directed downwardly at any desired angle on the beans or other objects traveling over the grating 24. One of the end connecting pipes 57 is attached to a hose 59 which in turn is connected to a suitable source of rinsing water.

In explaining the operation of the washer as thus far described, let it be assumed that the washer is to be used for string beans. Water is delivered into the washing pan 10 through the hose 48 and inlet 46 until the washing pan is filled up to the level of the lower end of the grating 24. As further water is delivered into the pan the overflow then passes into the trough 22 and is discharged through the drain 25. When the motor 43 is turned on a rapid oscillating motion is imparted to the hollow shaft or sleeve 29 on the shaft 15. The arms 17 oscillate with the sleeve 29 through a small arc and in turn impart oscillatory or vibratory movement to the washing pan 10 and thus to the rear pair of rockable arms 18. The beans are delivered from the hopper 51 by means of the conveyor 50 into the rear end of the washing pan 10 and the washing process begins.

Due to the fact that the two pairs of rockable arms 17 and 18, on which the washing pan 10 is mounted, are not parallel and to the fact that the rear pair of arms 18 is inclined at a greater angle from the vertical than the forward pair of arms 17, a special composite vibratory movement will be imparted to the pan 10, producing a particular predetermined effect which can be best explained with reference to Figs. 4, 5 and 6. Fig. 4 illustrates the position of the pairs of arms 17 and 18 and of the pan 10 at the beginning of each oscillatory movement towards the right. Fig. 5 correspondingly illustrates their positions at the beginning of each return oscillatory movement towards the left. The arms 17 and 18, as previously indicated, oscillate in comparatively small arcs. Due to the fact that the rear pair of arms 18 slope rearwardly at a greater angle from the vertical than the arms 17, each movement of the washing pan to the right results in a greater upward movement being imparted to the rear end of the pan than to the forward end, and correspondingly with each return movement of the pan to the left, the rear end of the pan moves the same greater distance downwardly. The upward and downward movement of the rear end of the pan would be represented by the difference in the lengths of the two lines B, B' of Figs. 4 and 5, and the upward and downward movement of the forward end of the pan would likewise be represented by the almost negligible difference in the lengths of the lines A, A'.

When this particular composite vibratory

6

movement is imparted to the washing pan 10, three interesting effects occur which can clearly be observed, namely:

(a) Pyramids of water, oscillating up and down, cover the surface of the water in the pan, the pyramids being highest at the rear end of the pan and gradually decreasing in height towards the front end. The resulting water turbulence causes the beans to be turned over and over and thus causes them all to be submerged at least part of the time, which insures thorough washing of the beans in the pan.

(b) The beans will travel from the rear end of the pan to the forward end, regardless of whether there is a continuous flow of water through the pan or not and will continue this forward travel along the inclined bottom 19, thence along the inclined grating 24, and finally along the inclined final bottom section 23 until they are discharged from the forward end of the pan.

(c) All the beans, as they travel along the washing pan, will take positions parallel to the line of travel, as indicated in Fig. 6, and will remain in such position constantly, even while traveling over the grating 24 and over the final bottom section 23. Thus, when delivered from the washer, the beans will all be parallel.

Dirt and foreign matter removed from the beans or other articles during the washing of the same in the washing pan 10 passes out through the grating 24 and the trough drain 25 as a result of both the flow of washing water through the washing pan and the composite vibratory movement of the pan. Consequently the pan is continually being cleared of the dirt, etc., washed from the beans or other articles during the operation of my device.

As the beans pass over the grating 24 the washing water will be drained from them and, if desired, they can at the same time be subjected to sprays of rinsing water from the shower pipes 56. I prefer to have the showers or sprays from the shower pipes 56 directed obliquely downwardly in the opposite direction from that in which the beans are traveling to insure thorough rinsing and draining of the beans as they pass over the grating 24. As long as the water sprays from the shower pipes 56 are not strong enough to move the individual beans the travel of the beans over the grating 24 will not be impeded by having the beans subjected to the rinsing sprays.

A transversely moving conveyor belt can be stationed under the discharging end of the final bottom section 23 of the washing pan, if desired, in order that the washed and rinsed and parallelly arranged beans can be conveyed to any convenient place; or a drier, indicated in general by the reference character 61, can be positioned beyond the washer, as illustrated in Fig. 9, so that the beans will pass from the discharge end of the washer on to the rear end of the drier.

The drier 61 resembles the washer in that a vibrating draining and drying pan 62, mounted and vibrated in the same manner as the washing pan 10, has an upwardly sloping bottom 63 along which the beans travel. The bottom 63, however, consists of a screen or perforated plate in order to permit any further water remaining on the beans to drain off and pass down into a stationary collecting pan 64, which in turn is provided with a drain 65. Air pipes 66 extend transversely across the frame of the drier above the vibrating screen pan and warm air under

pressure, obtained from any suitable source, is discharged from small orifices along the bottom of these pipes to facilitate the drying of the beans. Upon leaving the drier the beans then pass on to a conveyor belt 67.

Since the drier screen pan receives substantially the same composite vibratory movement as described with reference to the washing pan 10, the beans will continue to travel along the drier in the same manner as previously explained, and when discharged from the drier will all be substantially parallel to their line of travel. In the canning of string beans, as well known, unless the beans are to be cut up before canning, it is necessary to arrange the beans parallel to each other and to place them in the can or jar so that they extend up and down; otherwise it is impossible to fill the can or jar properly with whole string beans. The fact that, with my invention, the beans are automatically arranged parallel to each other greatly reduces the manual work required in placing the beans in the cans or jars.

Although I have described my invention as employed specifically for the washing of string beans, obviously it can be employed in similar manner in the washing of other small vegetables, fruits, berries, or other articles. However, thus far I have found the greatest field of utility for my invention to be in the washing of string beans, since with my invention, the beans are not only washed so satisfactorily and quickly with so little care and supervision, but also because of the unique feature as a result of which the beans are automatically delivered in parallel arrangement. It is only fairly recently that washing has been considered necessary in the processing or canning of string beans. However, due to the increased use of sprays and spray fertilizer in the growing of string beans, satisfactory means for washing the beans are required to meet a rapidly developing need for the same.

In all other fruit and vegetable washers of which I have any knowledge, a constant flow of the water is necessary to keep the objects moving properly through the washer. One of the main features of my invention, as previously mentioned, is that the forward movement of the articles through the washer takes place entirely independently of any flow of the washing liquid. This incidentally makes possible a certain economy in the use of the washing water or liquid.

Various modifications within the scope of my invention could be made in the washer which I have illustrated and described. For example, the same principle could be employed for producing the required composite vibration if the washing pan were suspended by arms mounted on shafts located above the pan instead of below it. Adjustments in the relative angularity of the non-parallel pairs of arms can be made depending upon the slope of the inclined bottom of the washing pan and also upon the speed with which it is desired to have the objects pass through the washing pan. The volume and rate of the flow of washing water from one end of the pan to the other, in case a substantial continuous flow of washing water is employed, may also be a factor in influencing the speed of travel of the objects to be washed. Adjustments should be made for different fruits or vegetables, for example, if ripe raspberries are to be washed it is better to have the shower sprays from the shower pipes 56 sloping in the direction of travel of the raspberries

rather than against their direction of travel since there would be a stronger tendency for the raspberries to roll backwards on the grating under the shower sprays. Other adjustments, depending upon the nature of the vegetables or fruit to be washed will readily suggest themselves. In carrying out my invention it is necessary that the two pairs of rocking arms for the washing pan should never be parallel, that the pan be subjected to a composite vibration involving vertical and horizontal movement, that the comparative vertical movement be greater at the intake end of the pan than at the discharge end, and that the pan bottom should slope upwardly towards the discharge end. With such arrangement the composite vibration imparted to the pan will produce the desired controlled travel through the pan of the articles to be washed.

I claim:

1. In a vegetable and fruit washer of the character described, a washing pan having a bottom extending in a single plane and sloping continuously upwardly from the intake end to the discharge end, means for delivering water into the intake end of said pan, the water overflowing slowly at said discharge end, said pan supported on two pairs of pivotally-mounted rocker arms located near the intake and discharge ends of said pan respectively, said arms mounted to swing in substantially parallel vertical planes parallel to the longitudinal center line of said pan, the arms in each pair being parallel to each other and located on opposite sides of said pan respectively, all of said arms being inclined from the vertical in similar direction but the angle of inclination of the arms at said intake end being greater than that of the arms at said discharge end, and means for imparting a rapid oscillatory movement to said pan and arms, thereby causing said pan to be oscillated simultaneously in horizontal and vertical directions with the amount of vertical oscillation of said pan being greater at the intake end than at the discharge end, said pairs of arms being so arranged that they will raise said pan with their forward swing in the direction of said discharge end and lower said pan with their return rearward swing in each oscillation, whereby the resulting composite oscillatory vibration of said pan will cause the food articles to be washed, when deposited at said intake end, to be repeatedly immersed in the water in said pan and to travel to said discharge end in paths parallel to the longitudinal center line of said pan.
2. In a vegetable washer of the character described adapted particularly for string beans, a washing pan having a smooth bottom, sloping continuously upwardly from the intake end to the discharge end, means for delivering water at the intake end of said pan, the water overflowing slowly at said discharge end, a grating near the discharge end of said pan, said grating extending in the same upward sloping plane as the bottom of said pan and secured to said pan, said pan supported on two pairs of pivotally-mounted rocker arms located near the intake and discharge ends of said pan respectively, said arms mounted to swing in substantially parallel vertical planes parallel to the longitudinal center line of said pan, the arms in each pair being parallel to each other and located on opposite sides of said pan respectively, all of said arms being inclined from the vertical in similar direction but the angle of inclination of the arms at said intake end being greater than that of the

arms at said discharge end, and means for imparting a rapid oscillatory movement to said pan and arms, thereby causing said pan to be oscillated simultaneously in horizontal and vertical directions with the amount of vertical oscillation of said pan being greater at the intake end than at the discharge end, said pairs of arms being so arranged that they will raise said pan with their forward swing in the direction of said discharge end and lower said pan with their return rearward swing in each oscillation, whereby the resulting composite oscillatory vibration of said pan will cause the string beans to be washed, when deposited at said intake end, to be repeatedly immersed in the water in said pan and to travel to said discharge end and thence over said grating in paths parallel to the longitudinal center line of said pan and to arrange themselves in parallel alignment during such travel.

3. A vegetable and fruit washer of the character described including a washing pan having a bottom sloping continuously upwardly from the intake end to the discharge end, a grating near the discharge end of said pan, said grating extending in the same upward sloping plane as the bottom of said pan and secured to said pan, means for delivering water into the intake end of said pan, the water in said pan overflowing slowly through said grating, means below said grating for carrying off the overflow water from said pan, said pan supported on two pairs of pivotally-mounted rocker arms located near the intake and discharge ends of said pan respectively, said arms mounted to swing in substantially parallel vertical planes parallel to the longitudinal center line of said pan, the arms in each pair being parallel to each other and located on opposite sides of said pan respectively,

all of said arms being inclined from the vertical in similar direction but the angle of inclination of the arms at said intake end being greater than that of the arms at said discharge end, and means for imparting a rapid oscillatory movement to said pan and arms, thereby causing said pan to be oscillated simultaneously in horizontal and vertical directions with the amount of vertical oscillation of said pan being greater at the intake end than at the discharge end, said pairs of arms being so arranged that they will raise said pan with their forward swing in the direction of said discharge end and lower said pan with their return rearward swing in each oscillation, whereby the resulting composite oscillatory vibration of said pan will cause the food articles to be washed, when deposited at said intake end, to be repeatedly immersed in the water in said pan and to travel to said discharge end and thence over said grating in paths parallel to the longitudinal center line of said pan.

ARTHUR B. McLAUCHLAN.
